UNITED STATES PATENT OFFICE

2,536,890

LUBRICATOR FOR PERCUSSIVE TOOLS

Otto J. Schorer, Northampton, Mass., assignor
to Worthington Pump and Machinery Corporation, Harrison, N. J., a corporation of Delaware

Application May 24, 1947, Serial No. 750,222

1 Claim. (Cl. 184—55)

1

This invention relates to percussive tools and, more particularly, to an oiling or lubricating structure for pressure fluid actuated tie tampers, clay spades, paving breakers and the like.

An object of the present invention is to provide a simple, compact lubricating system and apparatus for percussive tools which will supply the necessary lubricating oil to the various working parts of the tool, utilizing the pulsations in the operating pressure fluid during operation of the tool to deliver the lubricating oil to the working parts of the tool.

Another object of the present invention is to utilize the handle or hand grip of the tool as a reservoir for the lubricating oil and to provide means to maintain an air pocket in the reservoir to insure discharge of oil upon each lower pressure pulsation in the pressure fluid during operation of the tool, which oil is subsequently delivered to the working parts of the tool during the high pressure pulsations.

With these and other objects in view, as may appear from the accompanying specification, the invention consists of various features of construction and combination of parts, which will be first described in connection with the accompanying drawings, showing a lubricator for percussive tools of a preferred form embodying the invention, and the features forming the invention will be specifically pointed out in the claims.

In the drawings:

Figure 1 is a longitudinal section through a percussive tool embodying the lubricating structure.

Figure 2 is a cross section taken on the line 2—2 of Figure 1.

Referring more particularly to the drawings, Figure 1 shows a longitudinal section through a pressure fluid operated tie tamper but it is to be understood that the invention may be applied to clay spades, paving breakers or similar percussive tools without departing from the spirit of the present invention.

The percussive tool includes the body cylinder 1 in which a hammer piston 2 is reciprocated by air under pressure and the control of the air under pressure to the tool is provided by a valve 3 which is held open by cam action on rotary plug 4 operated by a manual handle 5. The air under pressure enters the chamber 6 through the air inlet 7 and passes, when the valve 3 is off its seat into the annular chamber 7 from which it is delivered through the passageway 8 into the cylinder 1 for reciprocating

the hammer piston 2. The hammer piston 2 is reciprocated in the usual manner of tools of this type and the operating air under pressure exhausts on the forward stroke of the piston 2 through the exhaust 9, thus during operation of the percussive tool there will be low pulsations in the incoming operating pressure fluid during the exhaust period and high pressure pulsations during the power stroke of the piston 2.

10 The head 10 of the tool which is attached to the cylinder has a laterally extending handle 11 thereon which is gripped by one hand of the operator during operation and the hand grip 12 of the handle structure 11 is provided with a recess 13 therein forming a reservoir for lubricating oil. The recess 13 opens out through one end of the hand grip 12 to permit filling of the reservoir. The open end of the reservoir 13 is closed by a closure plug 14 which threads into the handle as shown at 15. The closure plug 14 has a recess therein extending inwardly from its inner end so that there will be, at all times, an air space in the reservoir 13 regardless of the quantity of oil in the reservoir due to the 20 fact that when the plug 14 is threaded into the threaded opening 15 a volume of air is entrapped within the recess 16.

The end of the reservoir 13 opposite the end in which the plug 14 is mounted is connected by 30 a small restricted passage 16 with a chamber 17 in which is positioned felt packing 19 or analogous material which will retard the free flow of lubricating oil into or through the chamber 17. The chamber 17 is connected by a passage 18 with the inlet 7 for air under pressure. During the low pulsation periods of the air pressure in the tool, while it is operating, the pressure of the air entrapped in the reservoir will force oil to flow from the reservoir through the 40 restricted passage 16 and felt packing in the chamber 17 through the passage 18 into the air inlet passage 7 and during the inlet or high pulsation periods of the pressure air this lubricating oil will pass with the inflowing air into the chamber 6, annular chamber 7 and through the passage 8 thereby lubricating the working parts of the tool.

It will be understood that the invention is not to be limited to the specific construction or arrangement of parts shown, but that they may be widely modified within the invention defined by the claim.

What is claimed is:

In a lubricator for percussive tools having a handle and a pressure fluid inlet passage to al-

ternately deliver high and low pressure for operation of the tool, a lubricant reservoir formed in said handle, a filling opening at one end of said reservoir and opening out through said handle, a conduit communicating with said pressure fluid inlet passage, a chamber connected to the end of said conduit and adjacent the lubricant reservoir, means for restricting flow of pressure fluid out of said reservoir including, a restricted passage connecting said reservoir and said chamber to allow pressure fluid to pass into and out of said reservoir, a porous pad carried by said chamber, and a recessed closure plug in said filling opening to provide an air pocket in the reservoir regardless of the quantity of oil whereby during the low pressure pulsation of the pressure fluid high pressure fluid prevented from escaping by the restricted passage will force oil to flow from said oil reservoir to said inlet passage.

OTTO J. SCHORER.
